[57] CLAIM

The ornamental design for a flywheel pulling tool, substantially as shown and described.

DESCRIPTION

FIG. 1 is a side elevational view of a flywheel pulling tool showing my new design;

FIG. 2 is a top plan view thereof;

FIG. 3 is a front elevational view thereof;

FIG. 4 is a rear elevational view thereof;

FIG. 5 is a bottom plan view thereof; and

FIG. 6 is a top plan view thereof looking in the direction perpendicular to the inclined surface shown in FIG. 1.

*Fig.2.**Fig.4.**Fig.1.**Fig.3.**Fig.5.**Fig.6.*
